UNITED STATES PATENT OFFICE.

OTTO SABIN, OF JOHNSTOWN, PENNSYLVANIA.

MINE CAR.

Application filed April 20, 1926. Serial No. 271,516.

This invention relates to cars and, while not limited thereto, relates more particularly to that class of cars used in and around industrial plants and mines, and has for its object 5 the provision of a car having a maximum of cubical capacity coupled with a relatively low height so as to be particularly adapted for use in mines having low head room.

Another object is to provide a car having 10 a novel construction whereby the car body is mounted directly on the axles without the use of the customary frame or bolster.

A further object is to provide a novel construction whereby the stresses and strains 15 delivered to the ends of the cars, due to the bumping of the cars together and pulling will be distributed from end to end of the cars and to the several cars of a train instead of being absorbed in the car body.

20 In the drawings—

Figure 1 is a plan view of a mine car constructed in accordance with this invention.

Figure 2 is a side elevation thereof.

Figure 3 is a longitudinal sectional elevation taken on the line III—III of Figure 1.

Figure 4 is a transverse sectional elevation taken on the line IV—IV of Figure 2.

Figure 5 is an enlarged fragmentary sectional view illustrating the details of the axle 30 construction and mounting.

Figure 6 is an enlarged fragmentary detail view of the portion of the car body having the axle attached thereto.

Figure 7 is a fragmentary sectional detail 35 of a portion of a modified form of axle in which the spindle is formed separately from the axle body.

Referring more particularly to the drawings, the letter A designates the car body as a 40 whole which is composed of metal. The body A has a lower portion composed of a bottom wall 2 and vertical side wall portions 3 formed integral, and an upper portion consisting of side wall extension portions composed of vertical side wall portions 4 joined to and forming 45 an extension of the vertical side walls 3, outwardly projecting horizontal extension wall portions 5 and outer vertical side wall portions 6. The wall portions 4, 5 and 6 are 50 all formed integral and, since the walls 4 are joined or secured to the side walls 3, the complete sides and ends of the body form a unitary self-supporting structure.

One end of the body is closed by a rigid or

fixed end wall 8, and the other end of the body 55 is closed by a swinging gate 9 supported by hinge-members 10 pivotally secured to the side wall portions 6 of the car body, as at 12.

The upper portions of the car body, composed of walls 4, 5 and 6, are cut away to form 60 wheel clearance recesses and raised cap members 13 are secured over said recesses to form a continuous side wall.

The car body A is mounted directly on a 65 pair of U-shaped axle members 14 without a bolster or under-frame. The axle members 14 are substantially U-shaped and extend across the underside of the bottom wall 2 of the body and up along the outside of each side of the car body into the wheel clearance recesses and have their upper ends projecting outwardly under the top wall of the cap members 13. The axle members are secured to the bottom and sides of the car body and serve as stiffening members for the body.

75 The axle members 14 may be formed by forging or casting, as desired, and are provided intermediate the ends of their side portions, which parallel the sides of the car body, with wheel carrying spindles 16. When the 80 axles 14 are formed of cast metal, the spindles 16 are formed integral therewith, as shown in Figure 5, while when the axles are forged, the side portions are provided with tapered apertures 17 and the spindles 16 are formed 85 separately and secured in the apertures 17 by upsetting or riveting the inner end 17a as shown in Figure 7.

The body of the car is provided with wooden bumper blocks 20 at each end of the bottom 90 wall 2 which project materially beyond the ends of the side walls 3 of the car.

The rear end of the bumper block 20 is supported and backed up by a Z bar member 21 secured to the bottom 2 of the car. An inclined plate 22 is secured to the bottom plate 2 of the car and extends upwardly and over the top of the bumper block so as to facilitate the endwise movement of the material in the car when the car is dumped.

100 A relatively heavy reinforcing bar 23 extends over the top of the bumper block 20 and is secured to said block and to said Z bar 21.

A bumper casting 24 is fitted over the top and forward end of the bumper block and 105 under the end of the bottom of the car body and is secured thereto. Through-bolts 26, or rivets, extend through the bumper casting 24,

reenforcing bar 23, bumper block 20 and car bottom 2, so as to tie all of such parts together as a unit.

5 A tie-bar 25 extends from end to end of the car along the upper or top face of the bottom wall 2, and is secured to the wall 2 and to the axle members 14 and also to the reenforcing bars 23 at each end of the car. The ends of the bar 25 are bent upwardly and extend outwardly parallel with and in spaced relation with the upper faces of the bumper blocks.

10 The space between the ends of the tie-bar 25 and the bumper castings 24 form receiving recesses for the standard coupling links 27, 15 and the tie-bar ends, bumper castings and bumper blocks are provided with aligned apertures to receive a coupling pin 28.

15 By providing the tie-bar 25, the strains and stresses delivered to the ends of the cars are 20 delivered throughout the length of the car to the next adjacent car, and not absorbed in the car body as would be the case if the bumper blocks were supported by the car body alone.

25 The axle members 14, by their novel shape and mounting, serve to stiffen the car body and also provide for a car construction having a minimum of overall height.

30 While I have shown and described certain specific embodiments of my invention, it will be understood that I do not wish to be limited thereto since various modifications may be made without departing from the scope thereof as defined in the appended claims.

I claim—

35 1. A mine car comprising a car body having a lower section composed of a bottom and side walls formed as a unitary self-supporting structure, and upper side extension portions secured to the upper edges of said side walls of 40 said lower section and composed of horizontal and vertical walls, end walls for closing the ends of said body, at least one of said end walls being hinged, a pair of U-shaped combined axle and body stiffening members extending along and secured directly to the bottom and sides of said lower section of said body, spindle members projecting from the portion of said axle and stiffening members extending along the sides of the lower section 45 of said body, and wheels journaled on said spindles.

50 2. A mine car comprising a car body having a lower section composed of a bottom and side walls formed as a unitary self-supporting structure, and upper side extension portions secured to the upper edges of said side walls of 55 said lower section and composed of horizontal and vertical walls, end walls for closing the ends of said body, at least one of said end walls being hinged, a pair of U-shaped combined axle and body stiffening members extending along and secured directly to the bottom and sides of said lower section of said body, spindle members projecting from the

portion of said axle and stiffening members 65 extending along the sides of the lower section of said body, wheels journaled on said spindles, and said upper side extension portions being projected upwardly to form clearance for said wheels.

70 3. A mine car comprising a car body having a lower section composed of a bottom and side walls formed as a unitary self-supporting structure, and upper side extension portions secured to the upper edges of said side walls 75 of said lower section and composed of horizontal and vertical walls, end walls for closing the ends of said body, at least one of said end walls being hinged, a pair of U-shaped combined axle and body stiffening members extending along and secured directly to the bottom and sides of said lower section of said body, spindle members projecting from the portion of said axle and stiffening members 80 extending along the sides of the lower section of said body, wheels journaled on said spindles, a bumper block secured to each end of said bottom wall of said body, a bumper casting fitted over each of said bumper blocks and secured to said blocks and said car body, and a longitudinally extending tie-bar extending along the bottom wall of said car body and secured to said bottom wall of said car body and said axle members and connected to said bumper blocks and bumper castings.

85 4. A mine car comprising a car body having a lower section composed of a bottom and side walls formed as a unitary self-supporting structure, and upper side extension portions secured to the upper edges of said side walls 90 of said lower section and composed of horizontal and vertical walls, end walls for closing the ends of said body, at least one of said end walls being hinged, a pair of U-shaped combined axle and body stiffening members extending along and secured directly to the bottom and sides of said lower section of said body, spindle members projecting from the portion of said axle and stiffening members 95 extending along the sides of the lower section of said body, wheels journaled on said spindles, a bumper block secured to each end of said bottom wall of said body, a bumper casting fitted over each of said bumper blocks and secured to said blocks and said car body, and a longitudinally extending tie-bar extending along the bottom wall of said car body and secured to said bottom wall of said car body and said axle members, said tie-bar 100 having its ends arranged to overlie the top of said bumper block in spaced relation to form the top support for a coupling pin, and bracket members connecting said tie-bar with said bumper blocks.

105 In testimony whereof, I have hereunto set my hand.

OTTO SANN.
